ELECTRICAL SIGNAL FIXTURE FOR BARBERS

Philip J. Molé, 2517 N. 78th Ave., Elmwood Park, Ill.

Filed Sept. 27, 1965, Ser. No. 87,192

Term of patent 3½ years

(Cl. D1—12)

FIG. 1

FIG. 2

FIG. 3

FIG. 1 is an elevational view of my electrical signal fixture for barbers;

FIG. 2 is an elevation thereof, with a section broken away, and looking at the left of FIG. 1;

FIG. 3 is a top plan view of my said fixture thereof, with a section broken away.

I claim:

The ornamental design for an electrical signal fixture for barbers, substantially as shown.
